UNITED STATES PATENT OFFICE.

CHARLES H. PERKINS, OF LAKEPORT, LACONIA, NEW HAMPSHIRE, ASSIGNEE TO
CRANE MANUFACTURING COMPANY, OF LAKEPORT, NEW HAMPSHIRE, A CORPO-
RATION OF NEW HAMPSHIRE.

KNITTING-MACHINE.

1,057,166.

Specification of Letters Patent. Patented Mar. 25, 1913.

Application filed October 18, 1912. Serial No. 726,473.

To all whom it may concern:

Be it known that I, CHARLES H. PERKINS, of Lakeport, in the city of Laconia, county of Belknap, and State of New Hampshire, have invented certain new and useful Improvements in Knitting-Machines, of which the following is a specification.

The present improvements relate to the throw-down or draw-in cams of knitting machines, the purpose being to aid in pushing the needles down at a steep angle when approaching the lowest drawing point, thereby avoiding making holes in the knitted fabric by preventing knots pulling upon the heads of the needles.

The improvements are illustrated in the accompanying drawings, wherein—

Figure 1, is an elevation of a draw-in cam made in accordance with the present invention. Figs. 2, 3 and 4, are detail views of the separate devices which make up the draw-in cam.

The draw-in cam to which the present invention relates is the cam which draws in the needles of the knitting machine, thereby drawing the newly formed loops through the preceding loops of the fabric. It corresponds, for example, to the cam shown at 4 and 5, in Fig. 17, of United States Letters Patent of John S. Crane, No. 1,027,034, May 21, 1912. The cam is shown complete in Fig. 1. It comprises a cam plate A, which, as shown in Fig. 4, is provided with a recess a, and with holes b, and c. Fitting within this recess is a block B, which, as shown in Fig. 3, has a recess d, a stud e, a projecting pin f, and a hole g, the stud e, and pin f, extending from the inner face of the block. A toothed wheel C, shown separately in Fig. 2, has an eye h, which fits and turns upon the stud e. The toothed wheel C, is placed upon the block B, with its eye h, fitting over the stud e, so that the wheel C, fits within the recess d, of the block. The block is then fitted within the recess a, of the cam plate A, and the projecting pin f, of the block fits within the plain hole c, of the cam plate; and the hole g, of the block registers with the screw-threaded hole b, of the cam plate A. The

block and cam plate are then united together by a screw D, as shown in Fig. 1. When the parts are thus united, the teeth of the wheel C, extend beyond the steepest portion i, of the cam track j, against which 55 the nibs of the needles run.

Assuming that the organization of the knitting machine is such that the needle cylinder rotates and the knitting cams are stationary (as in said Crane Patent, No. 60 1,027,034, although the invention is equally applicable to a knitting machine wherein the needle cylinder is stationary and the knitting cams rotate) the needle nibs will approach the cam in the direction indicated 65 by the arrow k, in Fig. 1. The needle nibs encounter the cam track j, of the draw-in cam and are thereby drawn in, first gradually and then with greater rapidity. Finally, the needle nibs encounter the pro- 70 jecting teeth of the draw-in wheel C, caus- 75 ing the wheel to rotate. At the same time, due to the engagement of the teeth and the needle nibs, the needles are moved downwardly at a steeper angle than can other- 75 wise be obtained and this steeper downward movement occurs near the lowest drawing point. The effect of this action is to get a longer stitch, or to get the required length of stitch by a more direct pull of the needle 80 when near the lowest drawing point, and the result is to avoid making holes in the fabric or breaking the yarn since the low position of the needle acted upon by the draw-in wheel is obtained while the follow- 85 ing needles still remain in a position where they are free to pass knots which may be in the yarn. These knots are passed freely without pulling upon the heads of the 90 needles.

I claim—

1. A draw-in cam for a knitting machine having a toothed draw-in wheel located within a recess near the lowest drawing point of the cam, the teeth of the wheel pro- 95 jecting beyond the cam track so as to be in the path of the needle nibs.

2. A draw-in cam for a knitting machine having a toothed draw-in wheel near the lowest drawing point of the cam, the teeth 100

of the wheel projecting beyond the cam track so as to be in the path of the needle nibs.

3. A draw-in cam for a knitting machine having a toothed draw-in wheel near the lowest drawing point of the cam, the teeth of the wheel being in the path of the needle nibs.

In witness whereof, I have hereunto signed my name in the presence of two subscribing witnesses.

CHARLES H. PERKINS.
